ATTORNEY

UNITED STATES PATENT OFFICE.

GASPAR GARCIA, OF HABANA, CUBA.

MULTIPLE HINGE HANGER.

Application filed October 21, 1927. Serial No. 227,664.

This invention relates to a new and useful device in the nature of a multiple hinged hanger especially adapted for the purpose of hanging clothes, garments or the like. The 5 said device comprises hinged or pivoted, extended arms adapted to be hinged or pivoted when not in use, so as to require a minimum amount of space.

The object of the invention is to provide a 10 multiple hinged hanger comprising certain adjustable features hereinafter more fully described, claimed and illustrated in the accompanying drawing.

Fig. 1 is a side elevational view of my im- 15 proved device.

Fig. 2 is a front elevational view thereof.

Fig. 3 is an enlarged fragmentary view thereof, partly in section.

Fig. 4 is a fragmentary front elevational 20 view, illustrating a further development of my improved device.

As here embodied my improved device 25 comprises a vertical member 10 or bar, having secured thereto, at the upper and lower extremities thereof, brackets 11 and 12. The brackets 11 and 12 are provided with rear side extended elements 13, 14 and 15, 16, respectively oppositely extended therefrom, and having formed therein apertures 17, adapted 30 to receive screws, bolts, studs or the like, as a means of securing my improved device to the wall of a room, or to any desired vertical surface, as may be desired.

The said brackets 11 and 12 are provided 35 with front extended elements 18 and 19, respectively having secured thereto, or integral therewith and extended therefrom, vertical studs 20 and 21 respectively. The above mentioned vertical bar 10 is provided with a plurality of front extended elements 22 preferably spaced or positioned equidistant from the said front extended elements 18 and 19 of the above mentioned brackets 11 and 12. The extended elements 22 of the bar 10, have secured thereto, or integral therewith and extended therefrom vertical studs 23, positioned in the same vertical plane as the above mentioned studs 20 and 21.

The rods 24 are secured to and extended 50 from the enlarged members 25 or extremities having formed therein apertures adapted to receive the said studs 20, 21 and 23, so as to permit the said rods 24 to be hinged or pivotally mounted thereon, and extended therefrom in a horizontal direction.

The vertical member 26 is provided with

upper and lower extended elements 27 and 60 28, slidably mounted in apertures formed in the brackets 29 and 30, respectively, secured to and extended from the above mentioned brackets 11 and 12. The vertical member 26 is provided with a plurality of tapered or angularly disposed side edges 31 adjacent to the said rods 24, in proximity to the enlarged members 25. The said angularly disposed 65 side edges 31 are located unequally from the said rods 24, the lower disposed side edge being positioned relatively in close proximity to the lower of the said rods 24. The threaded member 32 is provided with an enlarged 70 head 33 and is threadedly mounted in the said bracket 30 and is provided with a tapered extremity 33 adapted to engage in the serrations 34, formed in the extended element 28 of the vertical member 26. The latter described construction is such as will permit the said vertical member 26 to be securely held in any desired extended position.

The above described construction is such 75 as will permit the said rods 24 to be pivoted angularly in horizontal planes and to rest against the vertically inclined edges 31, so as to permit clothes, garments or the like to be hung on the said rods 24, so as not to interfere with clothes hung on the lower rods. 80 The screw 32 may be loosened and the vertical member 26 raised or lowered for simultaneously changing the points of resting of the rods 24 against the vertically inclined edges 31 for changing the horizontal angular 85 positions of the rods 24 relative to a wall to which the brackets 11 and 12 may be attached. 90

In Fig. 4 of the accompanying drawing, I 95 have shown a plurality of engaging members 35, pivotally mounted on the pins 36 secured to the vertical member 27. The said engaging members 35 have formed therein elongated slots 37 at or near the free extremities thereof, adapted to receive the threaded members 38, screws, bolts or the like, threadedly mounted in the vertical member 27. The above described construction is such as will permit the engaging members 35 to be extended somewhat beyond the angularly disposed edges 31 of the vertical member 27 so 100 as to limit the movement of the said rods 24 as may be desired to accommodate the articles hung on the said rods 24.

It is obvious that I have provided a means 105 of accommodating articles hung on my improved device, so as to permit the said articles to be hung thereon and suspended there-

from, so as not to interfere with one another.

Having thus described my invention what I claim as new and desire to secure by United States Letters Patent is:

- 5 1. In a device of the class described, a plurality of rods pivotally mounted on studs secured to extended elements of a vertical bar, and to extended elements of a bracket and a second bracket, a vertical member slidably 10 mounted in a bracket and a second bracket secured to and extended from the above mentioned brackets, said vertical rod provided with angularly disposed edges adapted to engage the said rods, as a means of limiting the 15 movement of the said rods.
2. In a device of the class described, a plurality of rods pivotally mounted for moving in a horizontal plane on studs connected with extended elements of a vertical bar, a vertical member slidably mounted in brackets connected with the vertical bar, and arranged for assuming various fixed positions, and provided with inclined edges arranged for engaging

the said rods for providing rests for the rods at points as determined by the said fixed positions of the vertical member.

3. In a device of the class described, a plurality of rods pivotally mounted for moving in a horizontal plane on studs connected with extended elements of a vertical bar, a vertical member slidably mounted in brackets connected with the vertical bar, and arranged for assuming various fixed positions, and provided with inclined edges arranged for engaging the said rods for providing rests for the rods at points as determined by the said fixed positions of the vertical member, and a plurality of members pivotally mounted on the vertical member adjacent the inclined edges thereof and arranged for assuming extended positions relative to the inclined edges for engaging the rods and providing the rest points.

In testimony whereof I have affixed my signature.

GASPAR GARCIA.
